RAILING

Louis Blum and William J. Horgan, Jr., Pittsburgh, Pa.,
assignors to Blumcraft of Pittsburgh, Pittsburgh, Pa., a
firm

Filed July 28, 1965, Ser. No. 86,318

Term of patent 14 years

(Cl. D13—7)

FIG. 1

FIG. 2

FIG. 3

FIG. 1 is a perspective view of a railing embodying our new design wherein the shading on the panels represents glass;

FIG. 2 is a sectional view along the line II—II of FIG. 1; and

FIG. 3 is a perspective view of another railing embodying our new design.

The characteristic features of the design reside in the portions shown in full lines.

The steps and wall shown in broken lines are disclosed for illustrative purposes only.

We claim:

The ornamental design for a railing, as shown and described.
